UNITED STATES PATENT OFFICE

CHARLES E. LUCKE, OF NEW YORK, N. Y., ASSIGNOR TO THE BABCOCK & WILCOX COMPANY, OF BAYONNE, NEW JERSEY, A CORPORATION OF NEW JERSEY

WATER TUBE BOILER

Application filed January 9, 1931. Serial No. 507,574.

This invention relates to water tube boilers, and more particularly to a water tube boiler characterized by a plurality of banks of parallel tubes baffled to provide a plurality of gas passes, one of the gas passes being through tubes disposed within the tubes of one of the banks of water tubes.

An object of the invention is to provide a water tube boiler with parallel inclined boiler tubes in connection with a combustion chamber, and a baffle so arranged that gases of combustion from the combustion chamber are directed across the tubes in more than one pass and then are directed through certain of the tubes.

Other objects will be apparent to those skilled in this particular art from the description in the specification in connection with the drawings in which—

20 Fig. 1 is a side view of a boiler;

Fig. 2 is an enlarged side view of a structural detail of the invention;

Fig. 3 is an end view, in section, taken along the line 3—3 of Fig. 1.

25 In the embodiment of the invention chosen for purposes of illustration, steam and water drum 1 is connected by means of nipples 2 to downtake headers 3. One end of a bank of tubes 4 is connected to the downtake headers 3, and the other end thereof is connected to uptake headers 5. In the bank of tubes 4 the outer tubes 40 have inner tubes 35 extending therethrough and through the headers. These tubes are so arranged with respect to 35 each other and the headers 3 and 5 that the tubes 35 are open to the hot gases of combustion in the boiler which will sweep therethrough, and the heat absorbing fluid (which may be water) used in the operation of the 40 boiler is contained in the space between the two tubes.

Nipples 6 connect the headers 3 with a second row of downtake headers 7 into which 45 are expanded one end of each of the water tubes 8; the other ends thereof are connected to the lower part of uptake headers 5. Steam and water circulators 9 connect the uptake headers 5 to the steam and water drum, completing the steam and water circulatory system. A mud drum 12, connected

to the lower downtake headers 7 by nipples 11, rests upon a block 13 of the boiler setting 15 and has an outside connection which extends through the boiler setting.

55 A baffle 20, including an upright portion 22 extending across the tube bank 4 and a lateral portion 21 resting upon the upper row of tubes of the lower bank, directs gases of combustion from the combustion chamber 30 up and across both banks of tubes and 60 down and across the upper bank of tubes 4 to a gas chamber 24 bounded by the upright portion 22 of the baffle and the lateral portion 21 of the baffle resting on the upper row of the lower tube bank. From this chamber 65 the gas enters a gas chamber 25 formed by the downtake headers 3 and nipples 6 in conjunction with one wall 26 of the boiler setting. Another gas chamber 27 is similarly formed by the wall 28 of the boiler 70 setting in connection with the headers 5. As the headers herein shown are of the inclined type and the walls 26 and 28 are substantially vertical, both gas chambers have 75 a substantially trapezoidal cross section which is so dimensioned that the size thereof at any particular point is substantially proportional to the amount of gas flowing therethrough at any time.

80 A superheater 25 is disposed between the bank of tubes 4 and 8 on the uptake side of the baffle 20. The inlet and outlet ends of this superheater extend through the upright section 22 of the baffle and are expanded respectively in inlet and outlet headers 17 and 85 18. These headers are located behind the baffle walls and are protected from the gases of combustion in the first boiler pass by the baffle.

90 In the operation of the boiler, the hot gases of combustion from the combustion chamber 30 will successively sweep across the bank of tubes 8, superheater 25 and the upper ends of the water tubes in the bank of tubes 4 on the side thereof adjacent the uptake headers, and will then be directed down across the lower ends of the tubes in the bank 4 into the gas chamber 24 and from there the gases of combustion will flow into the 95 chamber 25 and thence through the inner 100 chamber 27.

tubes 35 into the gas chamber 27 leading to the stack 29.

Fig. 2 shows a simple way of connecting the tubes of the bank 4 into one header. 5 The outer tube 40 is expanded in the header in the usual manner. The inner tube 35 extends through the tube 40 and through the header and is seated in an auxiliary seat portion 36 which is fitted in the outer wall 10 of the header and secured by a suitable nut 37. This construction provides an annular chamber between the tubes 40 and 35 which receives water from the header. The tube 35 is open to the gas chamber 22 and the 15 gases of combustion delivered to the combustion chamber flow therethrough.

The other end of tube 40 is expanded in the inner face of header 5 in the usual manner, and the tube 35 is expanded in a plate 20 41 which is attached to the outside face of the header 5. This manner of connecting the tubes with the header is such that steam and water may circulate in the annular chamber between the tubes 35 and 40, while 25 the tube 35 is open to the gas chambers 25 and 27 so that the gases of combustion will flow therethrough. While this manner of connecting the tubes is convenient and effective, and is such that they may be readily 30 removed at any time that a replacement is necessary, a specific manner of connecting the tubes is not contemplated as a part of this invention.

From the foregoing description it is apparent 35 that this invention provides a multiple gas pass water tube boiler which is compact and in which the effectiveness of heat transfer is extremely high as an additional heat absorbing surface exposed to hot 40 gases of combustion is provided in the space ordinarily taken up by water tubes alone.

Furthermore, a boiler of this character is provided in which the water tubes may be 45 straight and parallel and so spaced that an interdeck superheater may be readily utilized.

While a specific embodiment of the invention 50 has been described in some detail, it is understood that substitutions, changes, additions and omissions may be made therein within the spirit of the invention as defined by the appended claims.

What I claim is—

1. In combination, a combustion chamber, 55 a water tube boiler with two tube banks spaced apart vertically between front and rear uptake and downcomer headers, the uptake header being continuous across the space, the downcomer header being inter-

rupted and joined by nipples across the space, a baffle so constructed and arranged with respect to the tubes that it directs gases of combustion from said combustion chamber in two transverse passes, first across both upper and lower tube banks and second down across the upper bank ending in the space between them, gas tubes inside the tubes of the upper bank extending through their headers to the outside thereof, and connections to lead the gases from the end of the second transverse pass between said tube banks through the gas tubes of the upper tube bank. 70 75

2. In a water tube boiler, two tube banks spaced apart vertically between uptake and downcomer headers, a baffle associated with both tube banks forming first an upper gas pass between it and said uptake headers and second a downward gas pass across the upper tube bank ending in a space bounded by the tube banks, gas tubes inside some of the water tubes and extending through end connectors and through the outside thereof, chambers at each end of said tubes between the headers and boiler casing, and a connection from the end of the second pass to the gas chamber bounded by said downcomer headers through the gas tubes to a chamber bounded by said uptake headers on the other side. 80 85 90

3. In a water tube boiler, a bank of compound water tubes, a bank of water tubes spaced apart from the compound tubes and parallel thereto, located above a combustion chamber; a baffle resting upon the upper row 100 of the lower bank of tubes and supported thereby, including an upright and a lateral portion; a superheater disposed between the two banks of tubes, the banks of tubes and baffle being so constructed and arranged that the gases of combustion from the combustion chamber are directed successively across the lower bank of tubes, the superheater, one end 105 of the compound tubes and down across the other end of the compound tubes to a gas chamber and thence through the compound tubes. 110

4. In a water tube boiler, a bank of inclined compound tubes, a bank of water tubes parallel to the compound tubes disposed therebelow and above a combustion chamber, a superheater located between the two banks of tubes, a baffle including an upright and lateral portion so located with respect to the tubes that the gases of combustion from the combustion chamber are directed across the tubes in more than one pass and then through the compound tubes. 115 120 125

CHARLES E. LUCKE.
